UNITED STATES PATENT OFFICE.

RICHARD W. UHLIG, OF ARLINGTON, NEW JERSEY, ASSIGNOR TO ALLEN TYPEWRITER COMPANY, OF ALLENTOWN, PENNSYLVANIA, A COMPANY OF PENNSYLVANIA.

TYPEWRITING-MACHINE.

1,384,788.

Specification of Letters Patent. Patented July 19, 1921.

Application filed October 13, 1917. Serial No. 196,374.

To all whom it may concern:

Be it known that I, RICHARD W. UHLIG, a citizen of the United States, and a resident of Arlington, in the county of Hudson and State of New Jersey, have invented certain new and useful Improvements in Typewriting-Machines, of which the following is a specification.

This invention relates to typewriting machines and the like, and it is an object of the invention to provide improved means to hold and feed the paper around a cylindrical and rotatably supported platen.

It is a further object of the invention to provide improved means to line space the platen.

Another object of the invention is to provide improved adjustable means, commonly termed "margin stop mechanism" to limit the to and fro movements of the carriage and thereby regulate the beginning and ending of the line of writing, and to release said means to permit of writing beyond said predetermined limits.

In the drawings accompanying and forming a part of this specification Figure 1 is a front elevation of a platen carriage for typewriting machines, partly broken away, illustrating an embodiment of my improved means to hold and feed the paper around the platen.

Fig. 2 is a sectional end elevation, looking at the left of Fig. 1 showing the parts in normal paper holding and feeding position.

Fig. 3 is a view similar to Fig. 2 but showing the parts in paper releasing position.

Fig. 4 is a view similar to Fig. 1 showing an embodiment of my improved line spacing mechanism.

Fig. 5 is a view looking at the right of Fig. 4 with the platen rotating knob removed and showing the line spacing mechanism in normal inoperative position.

Fig. 6 is a view similar to Fig. 5 but showing the parts in position at the end of a line spacing movement.

Fig. 7 is a sectional end elevation of means to regulate the line spacing movement.

Fig. 8 is a sectional end elevation showing means to throw a detent, shown in Figs. 5, 6 and 7 in engagement with the ratchet wheel to retain the same against movement, out of engagement with said ratchet wheel.

Fig. 9 is an elevation looking at the back of Figs. 1 and 4 to illustrate my improved means to limit the to and fro movement of the carriage. 55

Fig. 10 is an end elevation looking at the right of Fig. 9 showing the parts in normal position. 60

Fig. 11 is a sectional view of Fig. 9 and showing stop mechanism to limit the movement of the carriage in letter space direction, showing the parts in normal position; and 65

Fig. 12 is a view similar to Fig. 11 but showing the parts in released position.

Similar characters of reference designate like parts throughout the different views of the drawings. 70

In the drawings I have shown an embodiment of my invention in connection with only so much of a typewriting machine of the front strike type as is essential to an understanding of the invention, in which a platen 12 is mounted upon an axle 13 journaled in the ends 14, 15 of a platen frame or carriage 16 mounted upon a support 17 by ball bearings 18 to have to and fro movement. The axle has knobs at opposite ends 75 whereby the platen may be rotated. 80

In Figs. 1 to 3 there is shown an embodiment of my improved means to hold and feed the paper around the platen 12 in which a table 19 to guide the paper around the platen extends between the ends 14, 15 of the platen frame and inclines downwardly with the forward end extending below and conforming to the curvature of the platen, and has a rod 23 secured thereto, which rod 90 is journaled at its ends in the ends of the platen frame to pivotally support the table. A roller 20 is rotatably carried by arms 31 fixed to the table to extend longitudinally of the platen forwardly of the table. This 95 roller is normally maintained in yielding engagement with the platen by a spring 22, in the form of a leaf spring fixed to the carriage with its free ends engaging with the paper table and tensioned to normally urge 100 the table toward the platen and thereby the feed roller 20 yielding into engagement with the platen. In feeding the paper to the platen it is inserted between the platen and table and guided by the latter to the right 105 between the platen and feed roller and there-

by fed around the platen, as the platen is rotated.

To release the feed roller to withdraw the paper from between roller and platen or for the purpose of adjusting the paper there is provided a lever 24 secured to the table supporting rod 23. By pulling this lever forward from the Fig. 2 to the Fig. 3 position rotary movement will be imparted to the rod 23 and the table rocked to move the forward end thereof against the tension of the spring 22 and therewith the feed roller away from the platen.

To lock the table with the feed roller in the released position shown in Fig. 3 a latch 25 is pivotally connected to the lever 24, as at 26, said latch having a bifurcated portion 27 to straddle the platen axle to guide and prevent the accidental throwing up of the same. The latch normally rests upon a pin 28 in the platen frame end, as shown in Fig. 2, but as the feed roller is moved to released position the latch will ride over said pin and the latter engage a notched portion 29 of the latch thereby locking the lever 24 in its forward position against the tension of the spring 22 and the feed roller out of engagement with the platen as shown in Fig. 3. To release the lever 24 it is only necessary to move the latch upward out of engagement with the pin 28 by engaging the forward end thereof which is in the form of a finger-piece when the spring 22 will return the parts to initial position. To maintain the paper against the platen at the printing point or line of writing the leading edge of the paper is directed beneath a rod 30 extending longitudinally of the platen carried by arms 31 pivotally carried at 32 by the platen frame, whereby said rod may be moved toward and away from the platen.

To line space the platen there is fixed to the platen axle a ratchet wheel 35 with which a pawl 36 co-operates, (Figs. 1 to 7). This pawl is pivotally supported by a carrier 37 having a finger-piece 38 hung on the platen axle. The pawl is adapted to have to and fro movement and has a pallet 39 at one end to engage the teeth of the ratchet wheel by gravity as the pawl carrier is moved rearward or in line spacing direction against the tension of a spring 40, this rearward movement being limited by the pawl engaging beneath a stop pin 41 projecting from the end of the platen frame and to which pin one end of the spring 40 is connected, the engagement of the pawl with this stop also serving to lock the pawl in engagement with a tooth of the ratchet wheel and thereby prevent overthrow of the platen during the line spacing movement thereof.

To limit the reverse movement of the pawl and thereby regulate the line spacing movement thereof there is provided a stop pin 42 projecting from an arm 43 hung on the

platen axle to have rotative movement and movement transverse to the platen axle, said pin engaging in a bifurcation at the end of the pawl opposite to the pallet. The arm 43 has a pin 44 (Fig. 7) projecting from the side opposite the pin 42 which is adapted to engage in either one of a series of notches 45 in the platen frame end, the upper end of the arm being formed with a finger piece whereby the arm may be given a longitudinal movement to withdraw the pin 44 from one of the notches 45 and insert it into another notch. One wall of the bifurcation at the end of the pawl, as at 46, is beveled to form a cam face whereby as the pawl is returned to initial position by the spring 40 after a line spacing movement has been imparted thereto said cam face will ride along the stop pin 42 thereby throwing and holding the pawl pallet out of engagement with the teeth of the ratchet wheel. The pawl is adapted to line space the platen a distance equivalent to one to three tooth spaces of the ratchet wheel, and it will be obvious that should the arm 43 be adjusted so that the arm pin 44 will engage in the notch 45 at the extreme left of Fig. 7 the platen will be line spaced a distance equivalent to three notches of the ratchet wheel, and when it is adjusted so that said pin engages in the notch 45 at the extreme right of Fig. 7 the platen will be spaced a distance equal to one tooth space of the ratchet wheel.

To retain the platen in position to which it is adjusted by the pawl there is provided a pivoted detent 48 normally urged to engage a tooth space of the ratchet wheel by a spring 49. To release said detent from the ratchet wheel and thereby the platen to permit of the free rotation of the platen by the platen knobs there is provided a lever 50 on the side of the platen frame end opposite to the detent 48 (Fig. 8), said lever having a cam portion 51 to co-operate with a pin extending laterally from the detent and through an opening in the platen frame end to move the detent against the tension of its spring 49 away from the ratchet wheel and lock it in such position when the lever is moved to the full line position shown in Fig. 8. The detent is released to engage with the ratchet wheel by moving the cam lever 50 to the dotted line position, Fig. 8.

To limit the to and fro movement of the platen carriage and thereby regulate the right and left hand margin of the line of writing fixed stops 52, 53 are provided on the platen frame or carriage support, the stop 52 controlling the left hand end margin of the line of writing, and the stop 53 the right hand end. Stops 54, 55 to co-operate with the stops 52, 53 are movable to and from with the platen carriage. These stops are carried by a notched bar 56 extending longitudinally of the platen and pivotally

supported at opposite ends in the platen frame ends. The stops comprise a member 57 having a part to engage in a notch in the top of the bar, and a member 58 pivotally connected to and bent to straddle the member 57 and having a part to engage in a notch in the bottom of the bar 56 opposite to the notch in which the stop member 57 engages and has a downwardly extending projection 59 to normally occupy a position in line with the stops 52, 53 in the normal position thereof. The stop 53 is supported and adapted to actuate line locking mechanism when engaged by the stop projection 59, but as this mechanism does not constitute a part of the present invention illustration and description thereof is not deemed necessary. The stop 55 co-operates with the stop 52 on the carriage support 17.

20 As stated the stop carrying bar 56 is pivotally supported and to impart rotative movement thereto to throw the stops carried thereby out of engagement or the path of movement of the stops 52, 53 to permit of writing beyond the predetermined beginning or ending of a line of writing the bar has a lever 60 fixed thereto. As this lever is moved forward the bar 56 will be rocked thereby throwing the stop projections 59 rearwardly, as shown in Fig. 12, away from the stops 52, 53. When the lever 60 is released the bar will drop by gravity to initial position.

The platen is advanced in letter space direction through an escapement (not shown) controlled pinion 62 meshing with a rack 63 pivotally connected to opposite ends of the platen frame and adapted to be thrown into and out of engagement with the pinion by a 40 finger lever 64 connected to the pivotal support of the rack. It is often found desirable to advance the carriage independent of the escapement controlled pinion 62 when the rack 63 is thrown out of engagement 45 with the pinion 62 (Fig. 12), and should it be desired to advance or retract the carriage beyond the right or left hand margin stops 52, 53 means are provided to simultaneously throw the margin stops 59 either out 50 of engagement with or the path of the stops 52, 53. For this purpose the rack lever 64 has a laterally projecting pin 65 to extend through an opening in the end 14 of the platen frame to engage with a projecting portion 66 of the bar actuating lever 60, this pin normally occupying the position with relation to the stop-carrying bar actuating lever 60 shown in Fig. 11. It will be obvious that as the rack 63 is released 60 from the pinion, or moved to the position shown in Fig. 12, the pin 65 engaging with the lever projection 66 will rock the bar 56 to the position shown in said figure and throw the stops carried thereby either out 65 of engagement with or the path of the stops

52, 53. It will also be obvious that the bar 56 may be actuated by its lever independent of the actuation of the rack actuating lever 64.

Having thus described my invention, I claim:

1. In a typewriting machine, the combination with a to and fro movable carriage and a platen rotatably carried thereby, of a paper table having a part extending below and conforming to the curvature of the platen; a shaft to which the table is fixed rotatably mounted in the carriage; a roller carried at the forward edge of the table forwardly of and engaging with the platen; a spring carried by the carriage forwardly of the pivotal support of the table tensioned to normally urge the table in a direction with the roller in engagement with the platen; and a lever fixed to the pivotal support of the table to move the table and throw the roller out of engagement with the platen, and arranged with means to co-operate with means on the carriage to lock the table in said position.

2. In a typewriting machine, the combination with a to and fro movable carriage and a platen rotatably carried thereby, of a paper table pivotally supported by the carriage having a part extending below and conforming to the curvature of the platen and carrying a roller at the forward end thereof; a spring to yieldingly urge the table to position with the roller in engagement with the platen; a lever fixed to the table support operable to rock the support and move the table to position with the roller carried thereby out of engagement with the platen; and releasable latching means operable by the movement of the lever to lock the lever and thereby the table in position with the roller carried thereby out of engagement with the platen.

3. In a typewriting machine, the combination with a to and fro movable carriage and a platen rotatably carried thereby, of a paper table pivotally supported by the carriage having a part to extend below and conforming to the curvature of the platen, said table carrying a roller at the forward end thereof to extend longitudinally of the platen; a spring to yieldingly urge the forward end of the table toward the platen with the roller in engagement with the platen; a lever pivotally mounted on the carriage having a finger piece at one end and fixed to the pivotal support of the table at the opposite end and operable to impart movement to the support and table to throw the roller out of engagement with the platen; and a latch pivotally connected to and operable by the lever as the roller is thrown out of engagement with the platen to co-operate with a pin on the carriage to lock the table in position with the roller out of engagement.

- 4 with the platen, substantially as and for the purpose specified.
- 5 4. In a typewriting machine a frame to support a rotatable platen; a rock shaft mounted in the platen frame; a paper table to extend from the rear to below and to the front of the platen fixed to and carried by the rock shaft; a roller carried at the forward end of the table; a leaf spring secured between its ends to the platen frame with the free ends arranged to yieldingly urge the paper table to position with the roller in engagement with the platen; and a finger lever pivotally mounted on the 10 platen frame fixed at one end to the shaft and operable to rock the same to move the paper table to position with the roller out of engagement with the platen against the action of the spring.
- 15 5. In a typewriting machine a frame to support a rotatable platen; a rock shaft mounted in the platen frame; a paper table to extend from the rear to below and to the front of the platen fixed to and carried by the rock shaft; a roller carried at the forward end of the table; a leaf spring secured between the ends to the platen frame with the free ends arranged to yieldingly urge the paper table to position with the roller 15 in engagement with the platen; a finger lever connected to the shaft to rock the same to move the paper table to position with the roller out of engagement with the platen; a latch pivotally carried by the finger lever to engage a pin on the platen frame as the lever is operated to move the table to position with the roller out of engagement with the platen and retain the table in such position, said latch being arranged with a finger 20 piece to release it from said pin for the purpose specified.
- 25 6. In a typewriting machine a frame to support a rotatable platen; a rock shaft mounted in the platen frame; a paper table to extend from the rear to below and to the front of the platen fixed to and carried by the rock shaft; a roller carried at the forward end of the table; a leaf spring secured between its ends to the platen frame with the free ends arranged to yieldingly urge the paper table to position with the 25 roller in engagement with the platen; and a finger lever pivotally mounted on the platen frame and fixed at one end to the shaft and operable to rock the same to move
- 30 the paper table to position with the roller out of engagement with the platen against the action of the spring; and releasable latching means thrown to locking position to hold the paper table in position with the roller out of engagement with the platen when the table is moved to said position. 40
- 35 6. In a typewriting machine a frame to support a rotatable platen; a rock shaft carried by the platen frame; a paper table to extend from the rear to below and to the front of the platen fixed to and carried by the rock shaft; a roller carried at the forward end of the table; a leaf spring secured between the ends to the platen frame with the free ends arranged to yieldingly urge the paper table to position with the roller 45 in engagement with the platen; a finger lever connected to the shaft to rock the same to move the paper table to position with the roller out of engagement with the platen; a latch pivotally carried by the finger lever to engage a pin on the platen frame as the lever is operated to move the table to position with the roller out of engagement with the platen and retain the table in such position, said latch being arranged with a finger 50 piece to release it from said pin for the purpose specified.
- 55 Signed at New York city, in the county of New York and State of New York, this 21st day of July, 1917.
- 60 RICHARD W. UHLIG.
